(57) **CLAIM**

The ornamental design for an air filter for a robotic vacuum, as shown and described.

DESCRIPTION

FIG. 1 is a bottom perspective view of an air filter for a robotic vacuum showing my new design.

FIG. 2 is a front view of an air filter for a robotic vacuum showing my new design.

FIG. 3 is a rear view of an air filter for a robotic vacuum of showing my design.

FIG. 4 is a side view of an air filter for a robotic vacuum showing my new design.

FIG. 5 is another side view of an air filter for a robotic vacuum showing my new design.

FIG. 6 is a bottom view of an air filter for a robotic vacuum showing my new design; and,

FIG. 7 is a top view of an air filter for a robotic vacuum showing my new design.

The portions of the air filter depicted in broken lines are not part of the claimed design.
